UNITED STATES PATENT OFFICE.

WALLACE C. SABINE, OF BOSTON, MASSACHUSETTS, ASSIGNOR TO THE CARTER'S INK COMPANY, OF CAMBRIDGE, MASSACHUSETTS, A CORPORATION OF MASSACHUSETTS.

POUR-OUT FOR BOTTLES.

1,132,620.

Specification of Letters Patent. Patented Mar. 23, 1915.

Application filed August 7, 1912. Serial No. 713,789.

To all whom it may concern:

Be it known that I, WALLACE C. SABINE, of Boston, in the county of Suffolk and State of Massachusetts, a citizen of the 5 United States, have invented a new and useful Improvement in Pour-Outs for Bottles, of which the following is a full, clear, and exact description, reference being had to the accompanying drawings, forming a part of 10 this specification, in explaining its nature.

My invention relates to that type of pour-outs for bottles provided with an air inlet passage and a pour-out or outlet passage, and which is especially adapted for bottles 15 containing ink.

Among the objects of my invention is to provide a pour-out which will give an easy continuous stream, free from pulsation at all inclinations of the bottle irrespective of 20 the amount of ink in the bottle.

It is a further object of my invention to provide a pour-out with a means of closure which will effectively control the passages therethrough irrespective of the relative positions thereof; to provide a means of closure also which will form a permanent part of the pour-out and which when open will not interfere with the objects first above referred to, and which when closed will provide a positive seal for the bottle even though the bottle be in an inverted position as is often the case during shipment; also to provide a pour-out that can be economically manufactured.

35 My invention consists accordingly in a pour-out having a construction in accordance with the objects of my invention above referred to together, also, with various details of construction tending to make the 40 pour-out as simple and effective as possible, and all of which can best be seen and understood by reference to the drawings, in which—

Figure 1 shows in side elevation a bottle 45 having applied thereto a pour-out embodying the features of my invention. Fig. 2 is a plan looking at the pour-out from the under side thereof. Fig. 3 is a vertical section of the bottle and pour-out shown in 50 Fig. 1. Fig. 4 is the same as Fig. 3, excepting that the valve forming a part of the pour-out, as will hereinafter be explained, is occupying a different position than that shown in Fig. 3.

55 Referring to the drawings:—1 represents

the pour-out, 2 the bottle. The pour-out is in the nature of a cap applied to the top of the bottle closing the same and has the following construction and adaptability of parts.

3 represents the body of the pour-out. This may be made of any suitable material dependent upon the contents of the bottle. I prefer, however, that the same be made of hard rubber or other non-corrosive substance especially when the pour-out is used in connection with bottles containing ink. The body 3 of the pour-out is provided with an annular flange-forming edge or rim 4 adapted to fit over and rest upon the end of the neck of the bottle, a washer 5 being preferably interposed between the parts. It is by means of the shoulder formed by the rim or edge 4 that the pour-out is attached to the bottle. This effect is accomplished by 75 means of an annular clamp 6 which fits around the end of the neck of the bottle and is clamped to engage a bead 7 thereon, the clamp thence passing upwardly and around the edge 4 of the pour-out and being 80 crimped to engage the same thereby holding the pour-out securely applied to the bottle and providing a tight joint.

In order that the pour-out may fit centrally over the end of the bottle and to prevent also lateral displacement thereof, apart from that afforded by the clamp 6, I prefer that the body of the pour-out shall extend for a short distance into the hollow of the neck of the bottle. Such projection is indicated by the part 8 presenting an under bearing surface 9 which has special adaptability as will hereinafter be explained.

Upon one side of the body of the pour-out is provided with an upward extension 10 95 having a pour-out passage 11 through the same. The extension 10 is preferably made, at least in part, tubular in form and the passage 11 therein extends from the under side or face 9 of the body of the pour-out vertically through the same. In this connection, however, it is to be observed that the passage 11 does not extend straight through the extreme top end of the extension 10, but vents on the outer side thereof just adjacent the top end of the extension. This effect is obtained by closing the top end of the extension by a part 12 and slightly beveling the outer side of the extension adjacent the top to provide a face 13 in which the vent is 110

formed, the passage 11 at the upper end thereof being slightly curved on the inner side 14 thereof in order to conform to the vent thus provided. The advantage of this 5 is that as the bottle is tipped and the contents thereof flow outwardly through the pour-out passage, the disposition of the vent will act to properly guide and direct the stream, and when the bottle is returned to 10 its upright position any liquid that may remain in the pour-out passage will not dribble over the outside of the pour-out, but will flow back into the bottle. Such disposition of the vent or opening assists also in making 15 more effective the flow of liquid from the bottle.

Through the body of the pour-out on the side thereof opposite the pour-out passage 11 there is provided an air inlet passage or 20 opening 15. This passage is preferably one much shorter than the pour-out passage 11 and extends vertically from the under side or face 9 of the body of the pour-out, thence upwardly through the body to the atmosphere. 25 It will be further observed that the passages 11 and 15 are as widely separated from one another as the mouth of the bottle will permit and the outlet passage is carried upwardly through the extension 10 to a considerable height. This disposition of the 30 passages is for the purpose of obtaining a gravity head of ink even when the bottle is but slightly inclined, and enables the ink to flow freely after the bottle has once been 35 inclined sufficiently for the ink to flow. I have found that in order to obtain a proper flow of ink the essential consideration in the relation between the air inlet and pour-out 40 passages is the lateral distance between these passages and the vertical distance between the inner end of the intake passage and the outer end of the outlet passage, these being the points respectively at which the surface tension of capillarity acts to stop the flow. 45 It is also necessary that the two passages be separate and independent passages and that the inner ends thereof be as widely apart as possible and enter directly into the chamber of the bottle. If the air inlet passage and 50 outlet passage have a common communication with the main chamber of the bottle either through a common passage or connecting chamber, the result is a pulsating flow of the ink, producing splashing because 55 the air entering the intake passage invariably forms and separates in the form of bubbles. If these bubbles enter into the same chamber or passage through which the ink is flowing out the result is a pulsating 60 flow and splashing as aforesaid.

Between the openings 11 and 15 the body of the pour-out is provided with a further opening 16. This is a vertical opening extending from the under side or face 9 of 65 the body of the pour-out through the same.

I prefer that this opening may be of considerable length though less than the pour-out passage 11 and accordingly the body is extended by a portion 17 through which the opening 16 extends. The opening 16 is 70 adapted to receive the stem 18 of a valve 19 located adjacent the under side or face 9 of the body of the pour-out and which operates to control the respective air inlet and pour-out passages through the same, the body of 75 the pour-out and extended portion 17 thereof in which the opening 16 is formed, providing a bearing and guide for said stem by which it may be moved longitudinally 80 therein for controlling the position of said valve. The valve 19 is of a two-winged structure adapted to draw against the under side or face 9 of the body of the pour-out around and over the respective pour-out and air passages therein, closing the openings 85 into the same, or be moved away from said body, clearing the openings into said passages from the interior of the bottle. The valve is also adapted to fit snugly around that portion of the under side of said body 90 at the entrance to the opening 16 therein through which the stem of the valve extends to safeguard against the contents of the bottle escaping through this opening. I prefer also that the valve may be provided with a 95 washer 20 of some soft material carried by it to be drawn thereby against the under side of the pour-out, thereby affording a tight joint about the respective openings which the valve is tending to control when seated. 100 The valve 19 is purposely made a winged valve for closing individually the separate openings through the body of the pour-out in order that when open it may leave as little obstruction as possible between the inner ends of the inlet and outlet passages 105 and the main chamber of the bottle. Owing to the fact that the inner ends of the inlet and outlet passages are widely separated, if the valve controlling both were other than 110 a winged valve having individual closure for each passage, the tendency of such a valve would be to nearly close the neck of the bottle and form an ante-chamber between it and the bottom side of the pour-out resulting in the passage of air bubbles through this chamber beneath the valve into the outlet passage producing a pulsating flow 115 and consequent splashing as above referred to. To prevent turning of the valve and for the purpose also of guiding it to properly close over the respective openings in the pour-out, the valve is provided with a pin 120 21 projecting upwardly therefrom, parallel with the stem of the valve and adapted to enter and move within an opening or socket 125 22 formed within the body of the pour-out. The valve is controlled in the following manner: The stem of the valve extends upwardly through the opening 16 in the body 130

of the valve and to a point above the extended portion 17 thereof. The upper portion of the valve stem is threaded, and arranged to turn thereon, above the portion 17 of the body of the pour-out, is a milled nut 23. This nut is provided with a sleeve or extension 24 likewise threaded upon the valve stem and located within a socket 25 formed in the extended portion 17 of the body. At the bottom of this socket the body of the pour-out presents an edge or shoulder 26 against which the end of the sleeve or extension 24 is adapted to bear. The effect is accordingly obtained that as the nut is turned upon the stem, the extension thereof turning with it and bearing against said shoulder will move the valve stem longitudinally in one direction or the other and thereby operate to either draw the valve against the under side or face of the body of the pour-out closing the respective openings therein, or move the valve away therefrom clearing said openings and leaving free ingress thereto from the interior of the bottle depending upon the direction that the nut is turned. After the valve has been moved to an open position it might happen that as the bottle was inverted the valve might gravitate by the sliding of the valve stem to a closed position. To prevent this, however, the sleeve or extension 24, located within the socket 25 as aforesaid, is provided with an annular slot 26 in which is contained a spring ring 27 which is adapted to bear tensionally against the interior wall of the socket and operate by its frictional bearing to prevent the sliding of the valve stem within its bearing, thus preventing the valve from gravitating to a closed position after it has been moved to an open position.

The operation of using the pour-out is as follows: When the bottle is not in use and especially during shipment the valve is moved to a closed position simply by turning the milled nut 23 which operates to effectually seal the bottle. When the bottle is to be used the milled nut is simply turned in a reverse direction opening the valve, when the contents may flow therefrom in the usual manner. After such use the nut is reversely turned thereby closing the valve and again sealing the bottle.

Having thus fully described my invention, I claim and desire to secure by Letters Patent of the United States:—

1. A pour-out for bottles, the same comprising an attachable body having therethrough an air inlet passage and a pour-out passage, said passages being separate and independent of one another, oppositely arranged and extending respectively through the body from the under side thereof, said body having also therein an opening extending therethrough from the under side thereof and lying between said passages, a

valve controlling the passages and 'said opening through the body from the under side of the body, said valve having a stem extending through said opening, and means for controlling said valve through said stem. 70

2. A pour-out for bottles, the same comprising an attachable body having therethrough an air inlet passage and a pour-out passage, said body having an extension 75 through which said pour-out passage is continued, said passages being separate from one another, oppositely arranged and extending respectively through said body from the under side thereof, said body having also therethrough a further opening extending from the under side of said body and lying between said passages, a valve controlling the passages and said opening through the body from the under side of the body, said valve having a stem extending through said opening in the body, and means for controlling said valve through said stem. 80

3. A pour-out for bottles, the same comprising an attachable body having therethrough an air inlet passage and a pour-out passage, said passages being separate and independent of one another, oppositely arranged and extending respectively through 90 the body from the under side thereof, said body having also therein an opening extending therethrough from the under side thereof and lying between said passages, a winged valve having separate points of contact with the under side of said body for individually closing the passages and said opening therethrough, said valve having a stem extending through said opening, and means for controlling said valve through 95 said stem. 100

4. A pour-out for bottles, the same comprising an attachable body having therethrough an air inlet passage and a pour-out passage, said passages being separate and 110 independent of one another, oppositely arranged and extending respectively through the body from the under side thereof, said body having also therein an opening extending therethrough from the under side 115 of the body and lying between said passages, said opening at the top end of the body being enlarged to form a socket, a valve controlling the passages and said opening through the body from the under side of the body, said valve having a stem extending through said opening and socket, and a nut threaded upon said stem and contained within said socket. 120

5. A pour-out for bottles, the same comprising an attachable body having therethrough an air inlet passage and a pour-out passage, said body having an extension 125 through which said pour-out passage is continued, said passages being separate and in- 130

dependent of one another, oppositely arranged and extending respectively through the body from the under side thereof, said body having also therein an opening extending therethrough from the under side thereof and lying between said passages, said opening at the top of said body being enlarged to form a socket, a winged valve having separate points of contact with the 10 under side of said body for individually

closing the passages and said opening therethrough, said valve having a stem extending through said opening and socket, and a nut threaded upon the end of said stem and contained within said socket.
